UNITED STATES PATENT OFFICE.

HANS HENRIK NIELSEN, OF KOLDING, DENMARK.

MOTOR.

1,424,585.

Specification of Letters Patent. Patented Aug. 1, 1922.

Application filed September 18, 1919. Serial No. 324,589.

To all whom it may concern:

Be it known that I, HANS HENRIK NIELSEN, a subject of the King of Denmark, and resident of Kolding, in the Kingdom of Denmark, have invented new and useful Improvements in Motors (for which I have filed an application in Denmark on March 12, 1918, not patented), of which the following is a specification.

10 As well-known is the utilization of the fuel in explosion-motors very deficient, and one of the principal causes of this is the pollution of the gas mixture with the combustion-products in the cylinder.

15 My invention relates to improvements in motors for liquid and gaseous fuel, which augment the utilization of the fuel by preventing or counter-acting the said pollution, and which consist in placing a compression-chamber in the prolongation of the cylinder having the inlet-valve for the gas mixture and the igniting device at its top and the outlet-valve at its foot, in which chamber the injected gas mixture is compressed without being mixed with the combustion-products from preceding explosions.

20 The invention is illustrated in the accompanying drawing, which is showing a vertical section of the improved motor.

30 1 is the cylinder, in which the piston 2, working in four cycle, moves up and down. The cylinder 1 is according to the invention provided with a special compression-chamber 3, arranged as a narrowed cylindrical

35 prolongation of the cylinder 1. At the top of the chamber 3 the inlet-valve 4 is placed together with the igniting tube 5 or other igniting device. Finally there is on a fit place between the cylinder

40 and the chamber 3 arranged a flue 6 with an exhaust valve 7.

According to the invention the compression-chamber 3 is so big that its volume corresponds to about $\frac{1}{3}$ of the stroke-volume of the motor, and the inlet-valve 4 is thus arranged that the fuel entering through it will remain in the compression-chamber and during the compression-stroke be compressed in the said chamber, where it

50 is ignited, when the explosion has to take place.

The motor works in the following manner:

During the beginning of the downward motion of the piston the exhaust valve is still open, and it is held open, till the piston has moved from $\frac{1}{2}$ to $\frac{2}{3}$ of the length of the suction-stroke. Thereby so much air is taken in that the cylinder above the piston, or $\frac{1}{2}$ to $\frac{2}{3}$ of the volume of the stroke is filled with air, mixed with combustion-products, whereafter the outlet-valve is shut, while at the same time the inlet-valve is opened. During the further descending of the piston the mixture of air and combustion-products standing in the chamber 3 is expelled by the injected fresh gas mixture, so that the compression-chamber by the end of the suction-stroke will be quite filled with the fresh fuel, while the stroke-volume of the cylinder will be filled with a mixture of air and combustion-products. During the compression-stroke the entire contents of the cylinder and the compression-chamber are compressed into the chamber 3, where the fresh fuel will be standing uppermost in the upper third part or more of the chamber 3.

Now the ignition is effected by the igniting device, arranged in this upper part of the compression-chamber, and the explosion is done, the fresh fuel immediately exploding, thereby producing the maximum pressure of explosion. During the now following stroke of expansion, the piston is moving downward by the pressure of the explosion, and a little before the conclusion of the expansion stroke (however a little later than usual) the exhaust valve is opened, so that the pressure in the cylinder falls to the pressure of the atmosphere, when the piston reaches its lowest position. During the exhaust stroke the outlet-valve 7 is always open and remains so, till the suction-stroke is $\frac{2}{3}$ or $\frac{1}{2}$ effected, as before mentioned.

It is evident that the motor without departing from the principle of the invention, may be built as a motor of two cycles or of more than four cycles.

Having thus described my invention I claim:

50 In a motor the combination of a cylinder having a piston, a cylindrical prolongation

of the said cylinder forming a compression-chamber and having a volume of $\frac{1}{3}$ to $\frac{1}{2}$ of the stroke-volume, an inlet-valve for gas-mixture placed in the upper third part of the said compression-chamber and being adapted to remain shut during the first $\frac{1}{2}$ to $\frac{2}{3}$ of the suction-stroke, an igniting device placed in the upper third part of the said compression-chamber, and an exhaust-valve placed at the foot of the said compression-

chamber and above the said cylinder and being adapted to remain open during the first $\frac{1}{2}$ to $\frac{2}{3}$ of the suction-stroke, substantially as set forth.

In testimony whereof I affix my signature 15
in presence of two witnesses.

HANS HENRIK NIELSEN.
